Assistant Examiner — Samantha Lynne Brodowski

(74) Attorney, Agent, or Firm — Fross, Zelnick, Lehrman & Sissu PC; Charles T.J. Weigell, Esq.

(57) CLAIM

The ornamental design for a handbag, as shown and described.

DESCRIPTION

FIG. 1 is a first right side perspective view of a handbag showing my new design;

FIG. 2 is a front view thereof;

FIG. 3 is a back view thereof;

FIG. 4 is a left side perspective view thereof;

FIG. 5 is a second right side perspective view thereof;

FIG. 6 is a top perspective view thereof; and,

FIG. 7 is a bottom perspective view thereof.

The broken line depiction of the bag interior border in FIG. 7 illustrates an area comprising environmental matter that forms no part of the claim.

1 Claim, 7 Drawing Sheets(56)
